UNITED STATES PATENT OFFICE.

STEWART B. KING, OF HIGHLANDS, NEW JERSEY.

SKIFF.

1,352,753.

Specification of Letters Patent. Patented Sept. 14, 1920.

Application filed December 13, 1919. Serial No. 344,559.

To all whom it may concern:

Be it known that I, STEWART B. KING, a citizen of the United States, and a resident of Highlands, county of Monmouth, and State of New Jersey, have invented certain new and useful Improvements in Skiffs, of which the following is a specification.

This invention relates to an improved hull of a boat, and is particularly designed to be used in small boats, such as skiffs.

In some forms of boats, such as the kind known as Seabright skiffs, used off the coast of New Jersey, the small seaworthy boats are handicapped as to speed, due to a settling by the stern as the speed increases. To overcome this, and to provide a seaworthy boat capable of high speed, I have designed the hull which is the subject-matter of this invention.

I have devised a hull in which there are no radical changes to make the boat unfit as a surf boat, but have remodeled the portion astern of amidships to permit an increase of speed without any excessive settling by the stern, so that a much greater speed is possible with the same sized hull than in the skiffs as formerly used.

The invention is illustrated in the accompanying drawing, in which Figure 1 is a side view of a skiff made according to my invention. Fig. 2 is an enlarged side view of the stern, and Fig. 3 is an elevation of the stern.

The general form of the hull is of the usual type, the hull 10 being provided with a keel 11, which is usually curved at 12 where it merges into the stem 13. The bilge 14 forward of amidships is made so that it bulges outwardly and upwardly in a curve, as is usual in boats of this kind, but the bilge merges toward the rear, as at 15, to a more flattened shape, and this continues until it reaches the part 16, where it is concaved laterally, that is, it forms a slightly concave channel, in the usual size of skiff the "crown" of this concavity being about three-eighths of an inch.

This is clearly illustrated in Fig. 3 at 17, this showing the inwardly curved part which extends back to the stern 18, the keel 11 50 terminating short of the stern of the boat so that that part of the bottom of the boat that overhangs, as at 16, is downwardly and rearwardly inclined, as will be seen from Figs. 1 and 3, so that the surface 17 not only is 55 curved slightly inward transversely, but it extends downward toward the rear, the crown of this downward extension being from one-quarter to one-half inch.

Of course these curvatures and the amount 60 of curvature can be increased or diminished, according to circumstances, but I have found that with a boat built this way the speed can be very much greater than with the ordinary size of skiff, without the undue settling at 65 the stern, and the form of the hull that permits this does not at all affect the seaworthiness of the boat.

I claim:

1. A skiff having a hull with a keel terminating short of the stern, the overhanging part of the stern having a bottom inclined downwardly toward the rear. 70

2. A skiff having a hull with a keel terminating short of the stern, the overhanging part of the stern having a bottom inclined downwardly toward the rear, said downwardly inclined part being slightly concave transversely. 75

3. A skiff having a hull with a keel terminating short of the stern, and having the bilge forward of amidships bulging upwardly and outwardly and gradually flattening toward the stern until it forms a transversely concave and rearwardly and 85 downwardly inclined part where it overhangs the end of the keel. 80

In testimony that I claim the foregoing, I have hereto set my hand, this 11th day of December, 1919.

STEWART B. KING.
